Fig. 1

Fig. 2

To all whom it may concern:

Be it known that I, Alvin H. Martin, a citizen of the United States of America, residing at Moundsville, West Virginia, have invented a new, original, and ornamental Design for a Chalk Board or Similar Article, of which the following is a specification, reference being had to the accompanying drawing, forming part thereof.

Figure 1 is a perspective view of a chalk board or similar article, showing my new design; and

Figure 2 is a side elevational view thereof, to a reduced scale.

The dominant features of my new design are shown in solid lines in the drawing.

I claim:

The ornamental design for a chalk board or similar article, as shown and described.
